Patented Feb. 10. 1857.

Des. 870

J. E. Stevenson, of Albany, N.Y.
Letters Patent No. 870. Dated Feb. 16th 1857.

The Schedule referred to in these Letters Patent and making part of this same.

To all whom it may concern.

Be it known that I, James E. Stevenson, of the City and County of Albany and State of New York, have produced a new ornamental design for a cooking stove, and I do hereby declare that the annexed drawings are full and accurate delineations of the ornamental parts thereof.

What I claim as my production and desire to secure by Letters Patent is, the combination and arrangement of the ornamental design herein described and shown.
